UNITED STATES PATENT OFFICE.

BEATRICE J. YAEGER, OF MINNEAPOLIS, MINNESOTA.

SLEEVE-PROTECTOR.

1,284,536.

Specification of Letters Patent. Patented Nov. 12, 1918.

Application filed April 9, 1917. Serial No. 160,677.

To all whom it may concern:

Be it known that I, BEATRICE J. YAEGER, a citizen of the United States, residing at Minneapolis, in the county of Hennepin and State of Minnesota, have invented certain new and useful Improvements in Sleeve-Protectors; and I do hereby declare the following to be a full, clear, and exact description of the invention, such as will enable others skilled in the art to which it appertains to make and use the same.

My invention has for its object to provide a simple and extremely efficient sleeve protector especially adapted to be worn by book-keepers, stenographers, clerks, and other persons that work at a desk. It is, however, adapted for more general use and would be found very serviceable for use by women in their household or kitchen work while wearing a garment with long sleeves.

As a feature of the invention, it is made of a very light waterproofed silk cloth known to the trade as "rubberized oiled silk." The protector, however, involves features of novelty aside from the material of which it is made, and is preferably constructed as illustrated in the accompanying drawings wherein like characters indicate like parts throughout the several views.

Referring to the drawings:

Figure 1 is a perspective view showing a protector applied to a person's arm and covering a portion of the sleeve;

Fig. 2 is a plan view of the protector showing the cuff thereof closed;

Fig. 3 is a plan view of the sleeve showing the cuff thereof opened in part; and

Fig. 4 is an end elevation of the sleeve, some parts being broken away.

The body or sleeve portion 5 of the protector is tapered, so as to substantially fit the arm and, at its small end, it is formed with an outer cuff 6 and an inner cuff 7, which cuffs are longitudinally split or divided, respectively at 8 and 9. The outer cuff 6 is preferably formed integral with the sleeve 5 and is made double by turning the same inward and backward and stitching the same to the body at 10. The inner cuff 7 is attached to the sleeve 5 by the stitches 10, and at its extended edge, is provided with a hem 11 that contains an endless elastic cord or band 12. This cord 12 normally contracts or gathers the hem 11 but makes it expansible so that it will tightly fit the wrist or arm. The split edge 8 of the

outer cuff 6 is preferably bound or faced and is provided with separable fasteners 13 and 14 of the glove-fastener type. The inner cuff 7, at the outer extremity of its split edge 9 is also provided with a separable fastener 15, preferably of the glove-fastener type. By a fastener of the glove-fastener type, it will, of course, be understood is meant a fastener comprising a socket and a head adapted to be sprung into the socket, such as almost universally used on gloves.

Preferably, the sleeve 5 is made long enough to reach nearly to the elbow, and at its end, it is obliquely cut so that it may reach nearly or quite to the elbow on the underside and still clear the depression of the elbow joint at its upper side, and hence, will not be wrinkled by nor interfere with the elbow movement. The sleeve protector when made of material described, will not only be very light, but will have some stiffness, and because of its extreme smoothness, will not adhere to the sleeve of a garment over which it is placed, and hence, will maintain its shape and not tend to crumple up and work toward the hand. Moreover, it will be waterproof and will not collect dirt. Obviously, it may be easily washed if it should become soiled. It is, therefore, of a very sanitary nature.

The inner cuff completely protects the cuff of the garment sleeve while the outer cuff covers and protects the said inner cuff and gives a neat, finished appearance to the sleeve protector.

What I claim is:

1. A sleeve protector having a sleeve-like body and provided at one end with an inner and an outer cuff, the said outer cuff being longitudinally split and provided with separable fasteners, and the said inner cuff, at its edge, having a hem and an elastic cord within said hem.

2. A sleeve protector having a sleeve-like body and provided at one end with an inner and an outer cuff, the said outer cuff being longitudinally split and provided with separable fasteners, the said inner cuff, at its edge, having a hem and an elastic cord within said hem, the said hem and inner cuff being also split and provided with a separable fastener.

3. A sleeve protector having a sleeve-like body and provided at one end with an inner and an outer cuff, the said outer cuff being formed double with an inwardly and back-

wardly turned portion and the said inner cuff being separably formed, the inwardly and backwardly turned portion of said outer cuff and the said inner cuff being connected to the sleeve-like body by a common line of stitches.

4. A sleeve protector having a sleeve-like body and provided at one end with an inner and an outer cuff, the said outer cuff being longitudinally split and provided with separable fasteners, the said inner cuff, at its edge, having a hem and an elastic cord within said hem, the said hem and inner cuff being also split, and provided with a separable

fastener, the said outer cuff being formed 15 double with an inwardly and backwardly turned portion and the said inner cuff being separably formed, the inwardly and backwardly turned portion of said outer cuff and the said inner cuff being connected to the 20 sleeve-like body by a common line of stitches.

In testimony whereof I affix my signature in presence of two witnesses.

BEATRICE J. YAEGER.
